(57) **CLAIM**

The ornamental design for a collapsible and foldable rolling cooler, as shown and described.

DESCRIPTION

FIG. 1 is a perspective view of the collapsible and foldable rolling cooler of my design, showing in its fully open position;

FIG. 2 is a front elevational view thereof, shown in its collapsed position with the cover flap folded inwardly;
FIG. 3 is a side elevational view thereof, looking from the left side of FIG. 2, the opposite side being a mirror image thereof;

FIG. 4 is a rear elevational view thereof;

FIG. 5 is a top plan view thereof;

FIG. 6 is a bottom plan view thereof;

FIG. 7 is a front elevational view thereof in an alternate configuration, the cover flap is folded outwardly;

FIG. 8 is a side view of FIG. 7;

FIG. 9 is a top plan view of FIG. 7; and,

FIG. 10 is a bottom plan view of FIG. 7.
